(57) **CLAIM**

The ornamental design for a water bottle cap, as shown and described.

DESCRIPTION

FIG. 1 is a top-down perspective view of a water bottle cap showing my new design;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof;

FIG. 7 is a bottom plan view thereof; and,

FIG. 8 is a bottom-up perspective view thereof.

(Continued)

The broken lines are shown for the purpose of illustrating portions of the water bottle cap that form no part of the claimed design.

1 Claim, 8 Drawing Sheets
